FORCED AIR CIRCULATING HEATER

Robert T. Pearce, Moses Lake, Wash.

Application February 2, 1951, Serial No. 209,054

1 Claim. (Cl. 126—110)

1

The present invention relates to the broad class of heating appliances and more particularly to a forced air circulating heater.

One object of the invention lies in the provision of an air circulating heater with a central depression or well which has an air passage opening into the well at or adjacent its bottom and through which air passage air may enter the well and upon becoming heated, rise and pass from the mouth of the well.

Another object of the invention lies in the provision of a motor driven fan adapted to force the air into the well through the passage and thus create a forced circulation of the heated air.

Another object of the invention is to provide the air passage with an air baffle which directs the flow of the forced incoming air so that it will flow along the surface of the well and thus absorb the maximum amount of heat from the heated walls of the well and carry it into the area being heated.

Another object of the invention lies in the provision of means for adjusting the baffle towards and away from a seat at the mouth of the air passage and thus regulate the flow of air into the well according to the heat of the well and thus preclude over or under heating the walls of the well.

These and other objects of the invention will become apparent during the course of the following description.

In the drawings, forming a part of this specification, and in which like numerals are employed to designate like parts throughout the same,

Figure 1 is a perspective view of a floor type oil furnace embodying my invention and having a portion of the shell broken away for convenience of illustration.

Figure 2 is a vertical cross section taken through the furnace as at line 2—2 of Figure 1, and

Figure 3 is an enlarged fragmentary cross section showing the exhaust port of the air passage into the well and the adjustable baffle thereof.

Experiments have proven to me that the most economical method of extracting heat from any given fuel does not lie in the degree of combustion only but also in proper disposition of the heat produced by combustion. It therefore became apparent that the ideal method of heating, from an economical standpoint, was to maintain the heating appliance at the proper temperature for good combustion and also remove all of the excess heat by the air. To em-

body this invention in a working device, I have provided a floor furnace 4 which has the usual metal shell 5 and the grill 6 which forms a closure for the open top of the shell. The shell is formed with two side walls 7 and 8, end walls 9 and 10 and a bottom wall 11.

Within the shell 5, I have provided a metal fire box 12 which is circular in cross section and is shown as being an oil burner. It will be understood that any type fire box may be used which is adapted to any desired type fuel without changing the essence of my invention. The fire box shown has a bottom wall 13 and an upstanding circular wall 13' defining the fire box. Fire clay 14 or other suitable heat insulation is provided in the bottom of the fire box and a circular flange 15 is spaced above the top surface of the fire clay and rests upon the upstanding peripheral edge 14' of the fire clay 14. Spaced above the flange 15 is a second circular flange 16 which is supported upon multiple inwardly extending rivets or bosses 17 in the side wall 13' of the fire box. Each of the flanges is provided with a central opening as 18 and 19. A fuel supply tube 20 enters the fire box through one side thereof and admits the fuel oil from the regulator 21 for combustion. A supply pipe 22 enters the shell 5 and supplies the fuel oil to the regulator from a storage tank or source of supply (not shown). An opening or door (not shown) may be provided for lighting the fire or an electric fire starter may be installed.

Adjacent the top of the wall 13' and extending radially therefrom, I have formed a sleeve 23 which communicates with the fire box and is adapted to enter a regulation size stove pipe length 24, thus forming the flue connection to exhaust the smoke and fumes accompanying combustion.

Spaced co-axial shields 25 and 26 are positioned about the outside of the firebox and a natural air passage is thus formed between the wall 13' and the inside shield 25. Since the inside shield is preferably formed of metal, it will absorb a quantity of heat, and to prevent this heat from being transmitted to the shell 5, the second shield 26 is provided. The top edge of shields 25 and 26 are disposed at an inward angle as at 27 to direct the upwardly flowing heated air inwardly instead of allowing it to spread before it is emitted from the top grill.

Suitable brackets as 28 support the shields, fire box and a fan 30 from the bottom wall 11 of the furnace shell 5. To close the top of the firebox, I have provided

a cover 28 formed with a central well 29 and the well has a hemispherical bottom wall 30 disposed above the openings 18 and 19 of the circular flanges 15 and 16. An upwardly diverging conical side wall 31 extends from the bottom wall 30 and at its upper edge merges into a rolled top 32. The cover 28 thus appears circular when viewed in plan, and the rolled top appears semicircular when viewed in cross section as shown in Figure 2. The top 32 terminates in a downwardly extending outer edge 33 which is provided with an inwardly offset portion 34 adapted to fit within the fire box wall 13', and rivets 35 secure the cover 28 to the firebox 12.

Adjacent the bottom wall 30 of the well 29 and extending radially from the well, a sleeve 36 is pressed outwardly from the wall 31 and is adapted to receive a cast pipe or air passage 37 which extends from a motor driven fan 38 through fire box 12 and terminates in sleeve 36 of well 29. The air passage 37 is of such diameter as to fit tightly in the sleeve 36 and thus form an air tight seal between the well and the air passage.

A spider 39 is cast on the open inner end of air passage 37, and supports an internally threaded sleeve 40 at an angle thereto. A baffle plate 41 having a central depending threaded shank 42 threaded into sleeve 40 is supported thereby and adapted to form a variable or adjustable closure for the air inlet into the well 28. An angled peripheral edge face 43 is formed on the baffle, and a slot 44 is provided in its outer face to receive the bit of a screw driver for adjusting the baffle towards and away from the seat 45 formed about the inner opening of sleeve 36.

When the fire box is heated, the fan is turned on, and the baffle 41 is adjusted to allow the desired amount of air to be forced into the well, and to be directed by the baffle along the surface of the well where it will absorb the heat and carry it into the room. The well is thus kept at the lowest temperature found effective for adequate combustion of fuel in the fire box and since the heat produced is promptly re-

moved, less fuel is used to provide proper room temperature.

Having thus described my invention, what I claim as new and desire to secure by Letters Patent is:

In a forced air circulating heater the combination with a fire box having means for supplying fuel and a flue communicating with said fire box adjacent the top thereof for venting smoke and gases and means for supporting said firebox, of a cover for said fire box, a well in said cover, a downwardly converging conical inner wall forming the sides of said well, a hemispherical wall forming the bottom of said well, whereby said combustion smoke and gases pass upwardly about said well and heat the walls thereof, a horizontally extending sleeve adjacent the bottom of the well and communicating therewith, a motor driven fan positioned outside said fire box, an air duct passing through said fire box and terminating in said sleeve and communicating said fan with said well, a spider on the end of said air duct, an internally threaded sleeve supported by said spider and having the axis thereof extending substantially radially of said hemispherical wall, a baffle plate, a central depending threaded shank on said baffle plate threaded into said threaded sleeve, the peripheral underface of said baffle plate having a bevelled periphery, and a slot in said baffle plate, whereby the baffle plate may be adjusted toward and away from a seat about said sleeve to control the volume of air entering said well.

ROBERT T. PEARCE.
